(57) **ABSTRACT**

A printer includes a body, a cloth holder to hold a cloth thereon, a receiver to hold and move back and forth while holding the cloth holder partially within the body of the printer, and a printing unit to print an image on the cloth held by the cloth holder held on the receiver. The cloth holder is detachably attached to the receiver while holding the cloth thereon.

**PRINTER, CLOTH HOLDER, HOLDER
WITH CLOTH, AND CLOTH PRINTING
SYSTEM**

**CROSS-REFERENCE TO RELATED
APPLICATIONS**

This patent application is based on and claims priority pursuant to 35 U.S.C. § 119(a) to Japanese Patent Application Nos. 2016-093215, filed on May 6, 2016, and 2017-046489, filed on Mar. 10, 2017, in the Japan Patent Office, the entire disclosures of which are hereby incorporated by reference herein.

BACKGROUND

Technical Field

Embodiments of the present disclosure relate to a printer, a cloth holder that holds a cloth thereon, a holder with a cloth, and a cloth printing system that prints an image on the cloth.

Related Art

In a printer that prints an image on cloth including clothing such as T-shirts, etc., the cloth needs to be conveyed flat to a printing section disposed in a device body of the printer.

SUMMARY

One aspect of the present disclosure provides a novel printer that includes a cloth holder to hold a cloth thereon, a receiver to receive the cloth holder and move back and forth while holding the cloth holder partially within a body of the printer, and a printing unit to print an image on the cloth held by the cloth holder held on the receiver. The cloth holder is detachably attached to the receiver while holding the cloth thereon.

Another aspect of the present disclosure provides a novel cloth holder held by the receiver that reciprocates in a printer while holding the cloth holder partially within a body of the printer. The cloth holder holds a cloth with an image printed by a printer on the cloth holder. The cloth holder is detachably attachable while holding the cloth thereon.

Yet another aspect of the present disclosure provides a novel holder integral with a cloth. The holder holds the above-described cloth on the cloth holder. At least a portion of the cloth is smoothly held on the cloth holder.

Yet another aspect of the present disclosure provides a novel cloth printing system that includes the one or more of the above-described printers and a printing instruction issuing device connected to the one or more printers. The printing instruction issuing device connects with at least one of a preprocessing device that applies a printing operation preprocessing process to the cloth and a heater that heats the cloth with the image printed by the one or more printers. The printing instruction issuing device includes a printing controller to sequentially control the one or more printers.

BRIEF DESCRIPTION OF THE DRAWINGS

A more complete appreciation of the present disclosure and many of the attendant advantages of the present disclosure will be more readily obtained as substantially the same becomes better understood by reference to the following

2

detailed description when considered in connection with the accompanying drawings, wherein:

FIG. 1 is a perspective view schematically illustrating an exemplary exterior of a printer according to one embodiment of the present disclosure;

FIG. 2 is a perspective view illustrating an entire configuration of the printer according to one embodiment of the present disclosure;

FIG. 3 is a perspective view schematically illustrating the entire configuration of the printer taken from a direction different from that of a view of FIG. 2 according to one embodiment of the present disclosure;

FIG. 4 also is a perspective view schematically illustrating an exemplary cassette acting as a tray according to one embodiment of the present disclosure;

FIG. 5 is a perspective view illustrating an exemplary status of the cassette when a cover of the cassette is opened according to one embodiment of the present disclosure;

FIG. 6 is a cross-sectional view illustrating the cassette along a short direction of the cassette according to one embodiment of the present disclosure;

FIG. 7 is a perspective view illustrating an exemplary configuration of the cassette and a stage thereof according to one embodiment of the present disclosure;

FIG. 8 also is a perspective view illustrating an exemplary aspect of the printer when the cassette is attached to the stage according to one embodiment of the present disclosure;

FIG. 9 is a diagram schematically illustrating an exemplary aspect of the printer when the cassette is attached to the stage according to one embodiment of the present disclosure;

FIG. 10 is a perspective view illustrating an exemplary aspect of the printer when the cassette is attached to a device body during a power off state according to one embodiment of the present disclosure;

FIG. 11 is a perspective view illustrating an exemplary exterior of a fixing device that executes a fixing process by applying heat to an object according to one embodiment of the present disclosure;

FIG. 12 is a diagram illustrating an exemplary configuration of an interior of the fixing device of FIG. 11;

FIG. 13 is a cross-sectional view illustrating the cassette and surrounding thereof along a short direction of the cassette when a fixing process is executed according to one embodiment of the present disclosure;

FIG. 14 also is a cross-sectional view illustrating a cassette along a short direction of the cassette according to a second embodiment of the present disclosure;

FIG. 15 also is a cross-sectional view illustrating a cassette along a short direction of the cassette according to a third embodiment of the present disclosure;

FIG. 16 also is a cross-sectional view illustrating a cassette along a short direction of the cassette according to a fourth embodiment of the present disclosure;

FIG. 17 is a perspective view illustrating an exemplary cassette according to a fifth embodiment of the present disclosure;

FIG. 18 is a perspective exploded view illustrating the cassette of FIG. 17 when a cloth is held thereon according to the fifth embodiment of the present disclosure;

FIGS. 19A, 19B, and 19C are perspective views collectively illustrating a method of attaching a cloth to the cassette to be used according to the fifth embodiment of the present disclosure;

FIG. 20 is a cross-sectional view illustrating a cassette along a longitudinal direction of the cassette according to a sixth embodiment of the present disclosure;

FIG. 21 also is a cross-sectional view illustrating a cassette along a longitudinal direction of the cassette according to a seventh embodiment of the present disclosure;

FIG. 22 is again a cross-sectional view illustrating a cassette along a longitudinal direction of the cassette according to an eighth embodiment of the present disclosure;

FIG. 23 is a cross-sectional view illustrating a cassette along a longitudinal direction of the cassette according to a ninth embodiment of the present disclosure.

FIG. 24 is a perspective view illustrating another exemplary configuration of a detachably attachable cassette detachably attached to a cassette receiver according to one embodiment of the present disclosure;

FIG. 25 is a perspective view illustrating another exemplary cloth holder according to one embodiment of the present disclosure;

FIG. 26 is a diagram illustrating a tenth embodiment of the present disclosure;

FIG. 27 is a cross-sectional view schematically illustrating various exemplary preprocessing devices according to one embodiment of the present disclosure;

FIG. 28 is a diagram illustrating an exemplary cloth printing system according to an eleventh embodiment of the present disclosure;

FIG. 29 is a flowchart illustrating an exemplary sequence of printing an image on a cloth in the cloth printing system of FIG. 28 according to one embodiment of the present disclosure; and

FIG. 30 is a diagram illustrating an exemplary cassette identification device according to a twelfth embodiment of the present disclosure.

DETAILED DESCRIPTION

Referring now to the drawings, wherein like reference numerals designate identical or corresponding parts throughout the several views thereof, and in particular to FIGS. 1 to 3, one example of a printer according to one embodiment of the present disclosure is initially described. FIG. 1 schematically illustrates a perspective view of an exemplary exterior of a printer. FIG. 2 schematically illustrates a perspective view of an entire configuration of the printer. FIG. 3 schematically illustrates a perspective view of the entire configuration of the printer taken from a direction different from a direction in which the view of FIG. 2 is taken.

The printer 1 includes a stage 111 acting as a cassette receiver to detachably hold a cassette 200, which is a tray (as a cloth holder) to hold a cloth 400 thereon (see FIG. 6), and moves with the cassette 200 back and forth (i.e., reciprocates) in a device body 100. The printer 1 also includes a printing unit 112 that prints an image on the cloth 400 held on the cassette 200 also held on the stage 111 in the device body 100 as well. The printer 1 further includes an operation panel 104 to be operated by an operator, for example, to input the number of printing sheets.

As the cloth 400, not only a cloth formed in one sheet such as a handkerchief, a towel, etc., but also a cloth processed as a garment such as a T-shirt, a sweatshirt, etc., and a cloth constituting a part of a product, such as a tote bag, etc., are employed as well.

A carrier structure 113 is movably held on the device body 100 to move in a direction indicated by a double-headed arrow A (i.e., a carrying direction). The stage 111 is disposed on the carrier structure 113. The device body 100 includes a bottom housing 114 at a bottom thereof. A pair of carrier guides 115 is placed in the bottom housing 114 along the

direction indicated by arrow A. A pair of sliders 116 is correspondingly provided in the carrier structure 113 and is movably held by the pair of carrier guides 115, respectively.

The printing unit 112 includes a carriage 121 that moves on the stage 111 in directions as indicated by double-headed arrow B (i.e., in main scanning directions). The printing unit 112 also includes a head 122 mounted on the carriage 121 as well. The carriage 121 is movably held by a guide 123 also extended in the direction indicated by arrow B and is rendered to reciprocate in both directions indicated by arrow B by a driving motor 124 that transmits driving force thereto through a scanning mechanism such as a timing belt 125, etc. The head 122 is typically a liquid discharge head that forms an image by discharging ink on a surface of a cloth. However, the present disclosure is not limited to the head 122.

In this printer 1, after the cloth 400 is set to the cassette 200, the cassette 200 is mounted and held by the stage 111 located within the device body 100. Then, by repeatedly moving the head 122 in the directions indicated by double-headed arrow B while moving the stage 111 in one direction shown by double-headed arrow A, a prescribed image is printed on the cloth 400.

Now, with reference to FIGS. 4 to 6, one example of a cassette as a tray according to present disclosure is herein below described in detail.

FIG. 4 illustrates a perspective view of the cassette. FIG. 5 also illustrates a perspective view of the cassette when a peripheral cover of the cassette is opened. FIG. 6 illustrates a cross-sectional view illustrating of the cassette along a short direction of the cassette.

The cassette 200 includes a cassette base 201 as a tray base, and a platen 300 that acts as a cloth holder to hold a part of the cloth 400 flat to be printed thereon.

The platen 300 is configured by a platen structure 302 and a heat insulator 301 that constitutes a plane that holds the cloth 400 flat thereon. The heat insulator 301 has a heat resistance resistant to heat applied by a fixing device 5 described later in detail.

A platen peripheral cover 202 acting as the peripheral cover is attached to the cassette base 201 via a pair of hinges 203 and is openable in a direction indicated by an arrow indicated in FIG. 5. The platen peripheral cover 202 has an opening 202a in a portion corresponding to the platen 300, and presses the cloth 400 against a flange section 300a as an outer circumferential edge of the platen 300.

The platen 300 is supported above the cassette base 201 by multiple supporters 311 extending from the cassette base 201. Hence, the cassette base 201 and the platen 300 collectively form a cloth accommodating space 312 between these members to accommodate a surplus portion 400a of the cloth 400. For example, the surplus portion 400a may be both sleeves, a collar mouth, and a bottom edge or the like of a T-shirt when a front side of the T-shirt is printed.

Here, the platen 300 is detachably attached to the cassette base 201 and replaceable. With this, when multiple platens 300 are prepared, a clothing to be printed next is previously wrapped around one of the multiple platens 300 not used in a current printing. Hence, the printing of an image onto the next cloth can be started quickly by simply replacing the used platen 300 with a new platen 300 after printing and fixing process currently executed for the clothing are completed.

When the cloth 400 is set to the cassette 200, the platen peripheral cover 202 is opened and the cloth 400 is set onto (i.e., held by) the platen 300 as illustrated in FIG. 5. Subsequently, the platen peripheral cover 202 is closed as

illustrated in FIG. 4 while a surplus portion (i.e., a portion not printed) 400a of the cloth 400 is accommodated in an cloth accommodating space 312 as illustrated in FIG. 6.

When an image is printed on the cloth 400, the cassette 200 is attached (set) to the stage 111 in the device body 100 as illustrated in FIG. 1.

In this way, since the cloth 400 to be printed is set onto the platen 300 when the cassettes 200 is wholly drawn out of the device body 100, setting work of setting the cloth 400 to the platen 300 becomes easier.

Now, with reference to FIGS. 7 to 9, a mechanism of installing a cassette into the printer 1 is described in detail.

FIG. 7 illustrates a perspective view of an exemplary configuration of the cassette and a stage of the printer 1 of this embodiment of the present disclosure. FIG. 8 also illustrates a perspective view of an exemplary aspect when the cassette is attached to the stage of the printer 1 of this embodiment of the present disclosure. FIG. 9 is a cross-sectional view schematically illustrating an exemplary aspect when the cassette is attached to the stage of the printer 1 of this embodiment of the present disclosure.

As illustrated in FIG. 7, a pair of guide rails 131 and 131 is disposed at both ends of the stage 111 of the device body 100 in a direction perpendicular to the direction indicated by arrow A in which the stage 111 moves. At both sides of the cassette 200, a pair of grooves 211, into which the pair of guide rails 131 and 131 movably (i.e., slidably) fits, respectively, is disposed correspondingly.

A pair of depressions 132 and 132 is also disposed at both ends of the stage 111 in the direction perpendicular to the direction in which the stage 111 moves as indicated by arrow A. At positions of the depressions 132 and 132 (i.e., sliding end positions), the pair of grooves 211 and 211 stop moving along the pair of guide rails 131 and 131, respectively, in the direction indicated by arrow A. That is, the cassette 200 has a pair of convex portions 212 and 212 that fits into the pair of depressions 132 and 132 of the stage 111, respectively. Accordingly, these depressions 132 and 132 and the convex portions 212 and 212 collectively constitute a securing device that secures the cassette 200 and the stage 111 with each other when the cassette 200 is slid and set to the stage 111.

As configured in this way, when the cassette 200 with the platen 300 holding the cloth 400 thereon is to be attached to the stage 111 of the device body 100, the cassette 200 is slid and installed in the stage 111 in a direction indicated by arrow C along the direction of the movement of the stage 111 (i.e., the direction indicated by arrow A) as illustrated in FIG. 8.

Now, a procedure of installing the cassette 200 in the stage 111 is more specifically described with reference to FIG. 9.

First, a front edge of the cassette 200 is placed on the stage 111 as indicated by a two-dot chain line 200A. Subsequently, as indicated by a broken line 200B, the cassette 200 is further slid and deeply pressed in the direction indicated by arrow C with its pair of grooves 211 and 211 fitting into the pair of guide rails 131 and 131 of the stage 111, respectively.

Subsequently, when the cassette 200 is further pressed up to a sliding end as indicated by a solid line 200C, the convex portions 212 and 212 of the cassette 200 fit into the depressions 132 of the stage 111, respectively, thereby completing the installation of the cassette 200 in the stage 111.

Hence, since the cassette 200 can be mounted on the stage 111 in the same direction as the stage 111 moves, the device body 100 (i.e., the printer 1) can be more effectively downsized than a device body, in which the cassette 200 is

mounted on the stage 111 from right above the stage 111, because the stage 111 does not need to completely move out of the device body 100 and is exposed to an outside thereof.

However, a method of installing the cassette 200 in the printer 1 of the present disclosure is not limited to the above-described typical example. That is, for example, by removing an upper housing of the device body 100 and thereby opening a top of the stage 111 as illustrated in FIG. 2, the cassette 200 may be set to the stage 111 from above 10 the stage 111 in a direction indicated by arrow G as illustrated in FIG. 24. Even with this method, since the stage 111 does not need to be completely moved and exposed to the outside from the device body 100, the device body 100 can be downsized again. Further, beside the configuration of 15 removing the housing as described with reference to FIG. 2, a door structure, in which an upper section of the device body 100 is pivoted to the device body 100 and is opened, can be employed as well.

Now, an exemplary aspect when a power source stops 20 supplying power to the printer 1 that accommodates the cassette 200 in the device body 100 is described with reference to FIG. 10, which is a perspective view of an exemplary appearance of the printer 1.

On receiving an instruction to stop supplying power to the 25 device body 100 of the printer 1, a controller enables the stage 111 to move to a position at which a front side of the cassette 200 (i.e., a back side in a direction in which a cassette is attached) almost aligns with a front side of the device body 100 in planar view as illustrated in FIG. 10. 30 After that, power is turned off.

With this, a footprint of the printer 1 can be effectively reduced during a waiting time.

Now, with reference to FIGS. 11 and 13, an exemplary fixing device that fixes an object by applying heat thereto is 35 described. That is, FIG. 11 is a perspective view of an exemplary appearance of a fixing device 5 that executes fixing by applying heat to the object. FIG. 12 illustrates an exemplary configuration of an interior of the fixing device 5 of FIG. 11. FIG. 13 illustrates a cross-section of the fixing device 5 when the fixing device 5 currently executes a fixing process.

A fixing device 5 applies heat to a cloth 400 held on a platen 300 of a cassette 200. For this purpose, the fixing device 5 includes a cassette receiver 501 to which a cassette 200 is 45 detachably attached as set to the above-described printer 1. The fixing device 5 also includes a hot press unit 521 as a contact type heater that applies pressure and heat to the cloth 400 in a body 500 of the fixing device 5. Hence, the hot press unit 521 requires relatively high temperature of about 130 degrees or more, preferably about 150 degrees or more, for fixing.

A heat insulator 301 is included in the platen 300 and has heat resistance to resist heat having a prescribed degree of temperature (i.e., a fixing temperature) applied by the hot 55 press unit 521 of the fixing device 5.

In this way, since a surface contacting the cloth 400 on the platen 300 is made of a heat insulator, heating performance of the hot press unit 521 becomes more effective, because heat to be applied to the cloth 400 does not escape to either 60 a platen structure 302 or an interior of the cassette 200.

The heat insulator 301 can be made of heat-resistant sponge rubber made of silicone rubber, fluorocarbon rubber, various types of heat-resistant resin, felt, silicate calcium board, Kalhon, Kal Light, gypsum board, melamine sponge, 65 glass wool, and glass or the like. Since it is required to have certain measures of hardness and heat resistance to hold the platen 300 flat, the platen structure 302 is preferably com-

posed of either a metal plate or a glass plate and the like. Furthermore, different from a configuration illustrated in FIG. 13, the heat insulator 301 and the platen structure 302 are not necessarily independent (i.e., different bodies), and can be integrated together to constitute a single part.

The hot press unit 521 has a size sufficient to cover and contact the cloth 400 lying on the platen 300 (i.e., in a region of the heat-resistant platen structure 302).

Further, an openable cover 502 and an operation unit 504 are disposed on a front side of the body 500 of the fixing device 5. More specifically, the operation unit 504 is disposed at a position not to be operated unless the openable cover 502 is closed. In this example, the openable cover 502 is enabled to tilt to a front side, and the operation unit 504 is placed at a bottom of a front face of the body 500 of the fixing device 5.

With this, a risk that an operator accidentally touches the operation unit 504 and the hot press unit 521 starts operation accordingly and contacts the operator during installation of the cassette 200 can be avoided.

A structure for attaching and detaching the cassette 200 to and from a cassette receiver 501 is similar to that for attaching and detaching the cassette 200 to and from the stage 111 also acting as a cassette receiver in the above-described printer 1.

Hence, when the cloth 400 is to be set to the fixing device 5, the cassette 200 holding the cloth 400 with an image printed thereon is removed from the printer 1 as described above, and the openable cover 502 is then opened in a direction as indicated by arrow E in FIG. 12. Subsequently, the cassette 200 is inserted into the cassette receiver 501 of the fixing device 5 in a direction as indicated by arrow D in FIG. 11 and is finally held by the cassette receiver 501. Here, the cassette 200 is slid and set to the cassette receiver 501.

Then, the hot press unit 521 is lowered in a direction as indicated by arrow F in FIG. 13, and is depressed against the cloth 400 held on the platen 300 with the image printed thereon to heat the cloth 400 with the image.

Hence, the cassette 200 holding the cloth 400 thereon is shared by both the printer 1 and the fixing device 5 as well.

With this, the printed cloth 400 can be set to the fixing device 5 keeping the same state as that in the printing operation. Hence, even when it is carried, the printed cloth 400 does not wrinkle nor even partially overlap thereby preventing distortion of a printing surface thereof. Hence, efficiency of setting work of setting the cloth 400 by an operator greatly improves.

In addition, since the platen 300 holding the cloth 400 in the cassette 200 has a heat resistance to resist heat of the fixing device 5, the platen 300 neither deform nor cause a similar problem due to the heat.

As described heretofore, the fixing device 5 of this embodiment of the present disclosure is configured by using the hot press unit 521. However, the present disclosure is not limited to a type of the hot press unit 521 and can employ a different system, in which a cloth 400 is heated by a non-contact type heater as well. For example, a planar heater may be located adjacent to a surface of the cloth 400 at a distance of about 2 mm to about 3 mm to apply radiant heat thereto.

Although the cassette 200 is shared by both the printer 1 and the fixing device 5 as described heretofore, the present disclosure is not limited thereto. For example, when a preprocessing device applies thermo-pressing to a surface of the cloth 400 as a preprocessing process before printing to reduce fuzz of the cloth 400, the cassette 200 may be shared by both the preprocessing device and the printer 1 as well.

Further, the same cassette 200 can be utilized in each of processes of the preprocessing device, the printer, and fixing device as well.

Further, the printer 1 and a fixing device 5 or the like are placed side by side to share the cassette 200 and continuously apply respective processing operations to the cassette 200. In such a situation, since the same cassette 200 is commonly used, transportation thereof between these devices can be automated. In addition, when each of devices 10 such as the printer 1, the fixing device 5, etc., is downsized by using the cassette 200, multiple devices can be installed at the same time together in a single housing.

Now, another exemplary cassette of a second embodiment of the present disclosure is described with reference to FIG. 14.

FIG. 14 illustrates a cross-section of the cassette of the second embodiment of the present disclosure when viewed in a short direction thereof again.

A pair of side walls 221 stands up from respective edges 20 of a cassette base 201 of a cassette 200 to form side walls of a cloth accommodating space 312.

A platen peripheral cover 202 has an opening that faces a platen 300 thereby constituting a planar frame.

With this configuration, even when the platen peripheral 25 cover 202 is opened, an extra piece (i.e., a surplus portion) 400a of a cloth 400 can be reliably accommodated inside the cassette 200 due to provision of the side walls 221. That is, it can be prevented that the surplus portion 400a of the cloth 400 is sandwiched between the platen peripheral cover 202 and the cassette base 201 even when the surplus portion 400a of the cloth 400 protrudes.

Now, yet another exemplary cassette of a third embodiment of the present disclosure is described with reference to FIG. 15.

FIG. 15 illustrates a cross-sectional view of the cassette of the third embodiment of the present disclosure when viewed in a short direction thereof again.

A pair of side walls 221 stands up from respective edges of a cassette base 201 of a cassette 200 to partially form side 40 walls of a cloth accommodating space 312. Another pair of walls 222 downwardly extends from respective edges of a platen peripheral cover 202 to partially form the side walls of the cloth accommodating space 312 again.

Such a configuration can prevent protrusion of the surplus 45 portion 400a of the cloth 400 while widening a gap (i.e., an interval) between the platen 300 and each of the side walls 221 used to allow the surplus portion 400a of the cloth 400 to enter the cloth accommodating space 312 more than that used in the second embodiment of the present disclosure. Accordingly, work to accommodate the surplus portion 400a of the cloth 400 into the cloth accommodating space 312 becomes easier.

Now, yet another exemplary cassette of a fourth embodiment of the present disclosure is described with reference to FIG. 16.

FIG. 16 illustrates a cross-section of the cassette of the fourth embodiment of the present disclosure when viewed in a short direction thereof.

A pair of openable side walls 221 partially forming side 60 walls of a cloth accommodating space 312 is attached to shafts 223 at respective edges of a cassette base 201 of a cassette 200.

Such a configuration can prevent protrusion of a surplus portion 400a of a cloth 400 as in the second embodiment of the present disclosure while securing gaps used to accommodate the surplus portions 400a of the cloth 400 in the cloth accommodating space 312 as in the first embodiment

of the present disclosure as well. Accordingly, work to accommodate the surplus portion **400a** of the cloth **400** in the cloth accommodating space **312** becomes easier again.

Specifically, by tilting the side wall **221** (or side walls **221** and **221**) and then setting the cloth **400** onto a platen **300**, the surplus portion **400a** thereof can be more effectively accommodated in the cloth accommodating space **312** at the same time. In addition, by raising the side wall **221** (or the side walls **221** and **221**) after that before closing the platen peripheral cover **202**, the surplus portion **400a** is reliably accommodated in the cloth accommodating space **312** of the cassette **200**, thereby reliably preventing the surplus portion **400a** from protruding therefrom.

Now, yet another exemplary cassette of a fifth embodiment of the present disclosure is described with reference to FIGS. 17 and 18.

FIG. 17 is a perspective view of an exemplary cassette according to a fifth embodiment of the present disclosure. FIG. 18 also is a perspective view of an exemplary exploded state of the cassette of FIG. 17 when a cloth is held on the cassette.

A platen **300** is detachably attached to a cassette base **201** of a cassette **200**. In addition, a platen peripheral cover **202** is enabled to be detachable from the cassette base **201** and fit with an outer circumferential edge of the platen **300**.

Now, a method of attaching the cloth **400** to the cassette **200** of the fifth embodiment of the present disclosure is herein below described with additionally reference to FIGS. 19A to 19C. That is, FIGS. 19A, 19B, and 19C collectively illustrate exemplary steps of attaching the cloth **400** to the cassette **200** according to this embodiment of the present disclosure.

As described above with reference to FIG. 18, the platen **300** is initially removed from the cassette base **201**.

Then, as illustrated in FIG. 19A, the cloth **400** to be printed is spread with its back side (i.e., a face opposite a face to be printed) facing upward. Then, the platen **300** is placed on the back side of the cloth **400**. Subsequently, as illustrated in FIG. 19B, a surplus portion **400a** of the cloth **400** protruding from the platen **300** is folded to enter a back side of the platen **300**.

At this moment, since the platen **300** is detached from the cassette base **201**, a sufficient space needed to fold the cloth **400** can be secured around a section, to which the cloth **400** protrudes from the platen **300**. Hence, the surplus portion **400a** of the cloth **400** protruding from the platen **300** can be neatly folded.

Subsequently, as illustrated in FIGS. 19B and 19C, a pair of supporters (i.e., a pair of legs) **311** and **311** supporting the platen **300** fits into a pair of dents **206** formed on the cassette base **201**, respectively. The platen peripheral cover **202** is then fitted with the periphery of the platen **300**.

At this moment, since the surplus portion **400a** of the cloth **400** protruding from a plane of the platen **300** is neatly folded, flatness of a printed section in the cloth **400** increases when an outer circumferential portion of the cloth **400** is pressed by the platen peripheral cover **202**. This causes high quality printing.

Now, yet another exemplary cassette of a sixth embodiment of the present disclosure is described with reference to FIG. 20.

FIG. 20 illustrates a cross-section of the cassette of the sixth embodiment of the present disclosure when viewed in a longitudinal direction thereof.

As illustrated there, a pair of supporters **311** and **311** supporting a platen **300** is provided again and each of them includes a hollow pillar **231** disposed on a side of a cassette

base **201** acting as a base and another hollow pillar **331** disposed on a side of a platen **300** to movably fit with the hollow pillar **231**.

A pair of supporters **311** and **311** also includes a compression spring **332** disposed between the hollow pillar **231** and the other hollow pillar **331**.

With this, the platen **300** is supported to be displaceable relative to the cassette base **201** (in other words, a distance (i.e., a height) from the cassette base **201** to the platen **300** is changeable).

A platen peripheral cover **202** is also provided in this embodiment of the present disclosure to act as a cover to cover a periphery of the platen **300** again. A lock **204** is also provided to regulate a height of the platen peripheral cover **202** from the cassette base **201**. As illustrated in FIG. 20, a hinge **203** is located on the cassette base **201** to allow the platen peripheral cover **202** to pivot therearound. The lock **204** is located on the cassette base **201** on an opposite side to a side, at which the hinge **203** is located.

As configured in this way, when a cloth **400** (set to the platen **300**) has a different thickness (e.g., thicker than an average), the platen **300** is depressed against restoring force of the spring **332** while changing the distance (i.e., the height) from the cassette base **201**. Hence, the cassette of the sixth embodiment of the present disclosure can accommodate various cloths **400** having a different thickness.

In addition, with such a configuration, since the platen **300** is constantly pressed by a prescribed force against the platen peripheral cover **202**, the cloth **400** is unlikely deviate even when the cassette **200** is carried.

In addition, when a cloth **400** having a different thickness is set, the platen **300** is lowered to secure a prescribed gap between the platen **300** and the platen peripheral cover **202**. Accordingly, a height of the platen peripheral cover **202** from the cassette base **201** does not change.

In other words, a height of a surface of the cloth **400** held on the platen **300** is specified based on the height of the platen peripheral cover **202** from the cassette base **201**.

With this, a lock position, at which the platen peripheral cover **202** is locked regarding the cassette base **201** can be fixed by the lock **204**. Hence, a configuration of the cassette **200** can be simplified. In addition, since the lock position does not change, an operator can easily handle the cassette as well.

Further, when the head **122** (see FIGS. 2 and 3) employs a liquid discharge head, the shorter the distance between the head **122** and an a surface of a printing objective, to which liquid is given, the higher the quality of an image formed on the surface of the printing objective, in general.

In view of this, the platen **300** is configured to be displaceable and the circumferential edge of the movable platen **300** is pressed against the platen peripheral cover **202** to regulate the height of the surface of the cloth **400**. Hence, a quality of the image can be improved even when the cloth **400** having a different thickness is laid on the movable platen **300**.

In addition, when the platen **300** is displaceable in this way, it is preferable that the supporters **311** and **311** are supported on circumferential sides of the platen **300**, respectively, to secure parallelism of the surface of the platen **300** with a moving plane on which the head **122** moves. However, in such a configuration, the supporters **311** and **311** may hamper accommodation of the surplus portion **400a** of the cloth **400**.

In view of this, the height of the surface of the cloth **400** held on the platen **300** is regulated by the platen peripheral cover **202** at the height thereof to either place the supporters

311 and 311 inside a width of the platen 300 or reduce the number of supporters 311 as well. Hence, the surplus portion 400a of the cloth 400 can be readily accommodated in the cloth accommodating space 312.

Now, yet another exemplary cassette of a seventh embodiment of the present disclosure is described with reference to FIG. 21.

FIG. 21 illustrates a cross-sectional view of the cassette of the seventh embodiment of the present disclosure when viewed in a longitudinal direction thereof again.

This embodiment of the present disclosure includes a similar configuration to the above-described sixth embodiment except for the following configuration. That is, in the seventh embodiment, the hollow pillars 231 disposed on the side of the cassette base 201 and the hollow pillars 331 disposed on the side of the platen 300 are respectively engaged with each other via plays (or vertical gaps) formed between these hollow pillars 231 and 331. Hence, the platen 300 can be displaced even in an inclined state.

With this, when a cloth 400 having a different thickness therein, such as a cloth 400 partially having a double layer (e.g., a pocket or the like) is printed, the platen 300 inclines and equalizes heights of thin and thick portions of the cloth 400 with each other as illustrated in the drawing.

With this, since the flatness of the surface of the cloth 400 facing the head 122 can be secured, a high quality image can be again printed on even a cloth 400 partially having a different thickness therein.

For the same reason, fine adjustment of a height generally needed in accordance with a condition of the cloth 400 to be printed, such as presence of overlapping of multiple portions, inclusion of a pocket, presence of overlapping of seam portions, etc., becomes unnecessary. Accordingly, performance of setting work of setting the cloth 400 to the platen 300 can be effectively improved.

Now, yet another exemplary cassette of an eighth embodiment of the present disclosure is described with reference to FIG. 22.

FIG. 22 illustrates a cross-sectional view of the cassette of the eighth embodiment of the present disclosure when viewed in a longitudinal direction thereof again.

The cassette of this embodiment of the present disclosure at least includes the similar configuration to that of the cassette of the above-described sixth embodiment of the present disclosure. In addition, in the cassette of the eighth embodiment of the present disclosure, the platen 300 includes a guide rod 315 attached between two supporters 311 and 311. The cassette correspondingly includes a guide 205 on a side of the cassette base 201 to guide the guide rod 315. That is, the guide rod and the guide 205 collectively constitute a guide unit.

With this, such a configuration allows the platen 300 to precisely move when platen 300 displaces. In addition, when the platen 300 displaces, a force transmitted from an edge of the platen 300 to the supporters 311 and 311 is absorbed, thus preventing corruption of the supporters 311 and 311. Hence, the number of supporters 311 and 311 can be reduced, and accordingly, workability of accommodating the surplus portion 400a of the cloth 400 in the cloth accommodating space 312 can be enhanced as well.

Now, yet another exemplary cassette of a ninth embodiment of the present disclosure is described with reference to FIG. 23.

FIG. 23 illustrates a cross-sectional view of a cassette of the ninth embodiment of the present disclosure when viewed in a longitudinal direction thereof again.

The cassette 200 of this embodiment of the present disclosure includes the similar configuration to that of the cassette 200 of the above-described eighth embodiment of the present disclosure. As a difference, in this embodiment of the present disclosure, the cassette 200 is configured so that the platen 300 upwardly protrudes from the platen peripheral cover 202 by a length of Δh (delta h) when the platen 300 is lowered to a lower limit and the hollow pillar 231 accordingly hits against (i.e., contacts) the hollow pillar 331.

Hence, when a fixing process is applied to the cloth 400 by pressing the hot press unit 521 of the fixing device 5 against the cloth 400, since a prescribed pressure is given thereto, the fixing process is precisely executed.

That is, when the surface of the platen 300 is lowered below the surface of the platen peripheral cover 202 and the hot press unit 521 is then pressed, the cloth 400 held on the surface of the platen 300 no longer receives a required pressure from the hot press unit 521.

To solve such a problem, the lower limit of displacement of the platen 300 is regulated such that the surface of the platen 300 is not positioned lower than the surface of the platen peripheral cover 202 and the required pressure can be applied to the cloth 400.

Now, a tenth embodiment of the present disclosure is described with reference to FIGS. 26 and 27.

FIG. 26 illustrates exemplary usage of a cassette according to the tenth embodiment of the present disclosure.

In this embodiment of the present disclosure, a cassette 200 acting as a cloth holder is shared by a printer 1, a fixing device 5, and a preprocessing device 6 as well. That is, the preprocessing device 6 holds the cassette 200 and provides a preprocessing process to a cloth 400 held on the cassette 200. As the preprocessing process, the hot processing process employed in the above-described various embodiments of the present disclosure is typically employed to apply heat and pressure to a surface of the cloth 400 to minimize fuzz of the cloth 400 again. However, the preprocessing process is not limited thereto and may include a preprocess of removing surface wrinkles on the cloth 400 by ironing out the surface wrinkles and that of coating the cloth 400 with a fixing oil to either help fixing or prevent spreading of ink.

Here, various preprocessing devices that apply the fixing oil to the cloth 400 are described with reference to FIG. 27. That is, FIG. 27 illustrates cross sections of various exemplary preprocessing devices.

Each of the preprocessing devices 6 (i.e., 6a, 6b, and 6c) accommodates a preprocessing system 602 (i.e., 602a, 602b, and 602c) in an interior thereof surrounded by a housing 603 and a front cover 604. Here, although each of the preprocessing devices 6 includes the front cover 604, each of the preprocessing devices 6 can exclude the front cover 604 depending on a detail of a preprocessing process to enhance usability.

A detaching structure employed in each of the preprocessing devices 6 (i.e., 6a, 6b, and 6c) to attach and detach the cassette 200 to and from the cassette receiver 601 is identical with that to attach and detach the cassette 200 to and from the stage 111 of the printer 1. Otherwise, the detaching structure employed in each of the preprocessing devices 6 (i.e., 6a, 6b, and 6c) is identical with that to attach and detach the cassette 200 to and from the cassette receiver 501 of the fixing device 5 as well.

Hence, each of the preprocessing systems 602 (i.e., 602a, 602b, 602c) provides a preprocessing process to a cloth 400 mounted on the cassette 200 set to the preprocessing device 6.

As illustrated in FIG. 27, the preprocessing system 602a is an example that employs a roller coating system. The preprocessing system 602b is an example that employs a spray coating system. The preprocessing system 603c is also an example that employs a coating system using a liquid discharge system.

In this way, since the cassette receiver 601 to receive the cassette 200 has the same configuration to those (i.e., the stage 111 and the cassette receiver 501) of the printer 1 and the fixing device 5, a surface of the cloth 400 can be fixed (to the platen 300) with a same precision as those fixed (to the platen 300) in the printer 1 and the fixing device 5 as well. As a result, an optional preprocessing device can be easily prepared by optionally combining one of the preprocessing systems 602 (i.e., 602a, 602b, and 602c).

Now, an eleventh embodiment of the present disclosure is described with reference to FIGS. 28 and 29.

FIG. 28 illustrates an exemplary cloth printing system according to one embodiment of the present disclosure.

The cloth printing system includes one or more printers 1 (1a and 1b or the like) and one or more print instructing units 7 (i.e., terminals 7a, 7b, and 7c or the like). Each of the terminals 7 (7a, 7b, and 7c or the like) can connect with one or more fixing devices 5 (5a, 5b, and 5c or the like) and one or more preprocessing devices 6 (6a, 6b, and 6c or the like) that execute preprocessing processes before printing.

The terminals 7, the printers 1, the fixing devices 5, and the preprocessing devices 6 are connected respectively to each other either directly or via a wired or wireless network infrastructure. As illustrated in the drawing as one example, the terminals 7 are composed of computing terminals 7a and 7b and a tablet terminal 7c or the like. However, the terminals 7 of the present disclosure are not limited thereto and can be dedicated terminals as well.

Now, an exemplary sequence is herein below described with reference to FIG. 29 when the terminal 7b has a server function and acts as a printing instruction issuing device to control the cloth printing system.

When one of the terminals 7 acting as a printing instruction issuing terminal has issued and sends a printing instruction to the server terminal 7b in step S1, the server terminal 7b determines whether a preprocessing process is required based contents of the printing instruction in step S2.

When the server terminal 7b determines that the preprocessing is required (Yes, in step S2), the server terminal 7b selects an optimal preprocessing device 6 based on preprocessing contents, an installation location, and a condition of a device, and sends an preprocessing instruction thereto in step S3. When a preprocessing process is executed based on the preprocessing instruction in step S4 and is completed, the server terminal 7b further determines if either the same preprocessing process or another preprocessing process is again or newly needed back in step S3.

When the server terminal 7b determines that all preprocessing process has been completed (No, in step S2), the sequence subsequently goes to a step S5 in which a prescribed printer 1 is selected. That is, the server terminal 7b selects an optimal printer 1 based on contents of the printing instruction (e.g., the number of colors, a type of material, a quantity of ink needed or the like), an installation location, and a condition of a device, and then sends a printing instruction to the printer 1 as selected.

When the printing operation in step S6 is completed, the sequence goes to a step S7 to determine if a post processing process is needed.

When the server terminal 7b determines that the post processing process is needed, the server terminal 7b then

selects an optimum fixing device 5 based on the contents of the printing instruction (e.g., the number of colors, a type of material, and a quantity of ink needed or the like), an installation location, and a condition of a device in step S8.

5 The server terminal 7b subsequently sends a fixing processing instruction to the fixing device 5 as selected. When the fixing process in step S9 is completed, the server terminal 7b further determines if either the same post processing process or another post processing process is either again or newly 10 needed back in step S7. When the server terminal 7b determines that all post processing has been completed (No, in step S7), the printing process is terminated.

Thus, by sharing the same detachably attachable cassette 200 in the printer 1, the fixing device 5, and the preprocessing device 6 or the like and preparing multiple sets of these devices, printing operation can be continued without raising a trouble, such as long time waiting, stop of operation due to running out of ink, out of order of devices, etc.

Now, a twelfth embodiment of the present disclosure is 20 described with reference to FIG. 30.

FIG. 30 illustrates an exemplary cassette condition identifying system that identifies a cassette condition according to this embodiment of the present disclosure.

The cassette 200 includes an identifier 290 that holds 25 identification information at a prescribed portion thereof. The identifier 290 is preferably placed at a portion of the cassette 200 to be readily read when the cassette 200 is inserted into each of the device bodies of the printer 1, the fixing device 5, and the preprocessing device 6, respectively.

30 Correspondingly, an identification reader 190 is disposed, for example, in the stage 111 of the printer 1 to read (or detect) the identifier 290. Therefore, identification information can be detected from the identifier 290 of the cassette 200 set to the stage 111 of the printer 1. Similarly, the cassette receiver 501 of the fixing device 5 and the cassette receiver 601 of the preprocessing device 6 also include identification readers 190 for the same purpose, respectively, as well.

Such a cassette condition identifying system of the identifier 290 and the identification reader 190 can be either 40 contact or contactless types. The identifier 290 included in the cassette 200 includes an information storing device (i.e., a memory) to store information related to printing operation. The information storing device (i.e., the memory) of the identifier 290 stores various information, such as presence of preprocessing process executed by the preprocessing device 6, contents thereof (i.e., information that specifies the preprocessing device), a type of an image printed, experience of a preprocessing process before fixing, etc., beside time data.

45 With this, when the cloth printing system includes multiple terminals, inconvenience such as erroneous processing or printing for a cassette, etc., can be avoided. Therefore, even when multiple cassettes are prepared as the multiple devices, inconvenience in that a user needs to identify a cassette or printing is erroneously executed can be prevented. Hence, usability is further improved while avoiding the above-described problems.

As described heretofore, the cloth printing system includes the printer 1, the fixing device 5, and the preprocessing device 6. However, a specific configuration of the cloth printing system may be selected as needed in printing, and, for example, the cloth printing system does not contain one of the fixing device 5 and the preprocessing device 6 as well.

60 Here, the above-described cloth holder of the present disclosure is sufficient if it can be detachably attached to the printer and the fixing device. That is, the shape or the like is

15

not limited to a box type cassette as employed in the above-described various embodiments of the present disclosure. For example, as illustrated in FIG. 25 (only the printer 1 is illustrated), the cloth holder can be a sheet of a plate-like platen enabled to be inserted into the printer 1 and the fixing device 5 as well.

Further, as a device to eliminate a process of setting the cloth (i.e., the T-shirt or the like) to the cloth holder every time when printing is executed thereby improving workability of printing, a cloth holder with the cloth already set thereto can be also used. In such a situation, the used cloth holder is collected and a fresh cloth holder with a cloth set thereto is provided again. That is, the used cloth holder is replaced with the fresh cloth holder. In this way, by setting and smoothly holding the cloth on the cloth holder and thereby constituting the cloth holder integral with the cloth thereon, the cloth holder integral with the cloth can be put in a market as a target of a commercial transaction.

Further, to obtain a similar advantage to that described above, instead of the above-described platen detachably attached to the cloth holder, a platen with a cloth (e.g., a T-shirt) already set thereto can be utilized as well. In such a situation, the platen with the cloth set thereto is attached to the cloth holder, and printing and/or fixing processes are then applied thereto. The platen is removed from the cloth holder when the printing and/or fixing processes are completed. Then, a fresh platen with a new cloth already set thereto is installed in the cloth holder, and printing and/or fixing process are similarly applied thereto. In such a situation, the used platen is collected and the fresh platen with the fresh cloth set thereto is provided again. Similar to that as described above, by setting and smoothly holding the cloth on the platen and thereby constituting the cloth holder with the cloth thereon, the cloth holder integral with the cloth can be put in the market as the target of the commercial transaction again.

With this, since an operator is not needed to newly set a cloth (e.g., T-shirt) every time, a continuous operation handling multiple sheets becomes easier and can be automated as well.

Numerous additional modifications and variations of the present disclosure are possible in light of the above teachings. It is therefore to be understood that within the scope of the appended claims, the present disclosure may be executed otherwise than as specifically described herein. For example, the printer is not limited to the above-described various embodiments and may be altered as appropriate. Similarly, the cloth holder is not limited to the above-described various embodiments and may be altered as appropriate. Further, the holder integral with a cloth is not limited to the above-described various embodiments and may be altered as appropriate.

What is claimed is:

1. A printer comprising:
a body;
a cloth holder to hold a cloth on the cloth holder;
a receiver to receive and hold the cloth holder, the receiver movable back and forth while holding the cloth holder partially within the body of the printer;
a printing unit to print an image on the cloth held by the cloth holder held on the receiver,
wherein the cloth holder is detachably attachable to the receiver while holding the cloth on the cloth holder,
wherein the cloth holder includes:
a base;
a platen to hold flat a portion of the cloth to be printed;

16

a peripheral cover to sandwich the cloth together with the platen at a periphery of the platen; and
a cloth accommodating space formed between the platen and the base to accommodate a surplus portion of the cloth,
wherein the peripheral cover encloses the cloth accommodating space.

2. The printer according to claim 1, wherein the cloth holder is mounted on the receiver by sliding the cloth holder in a direction in which the receiver moves.

3. The printer according to claim 1, wherein one of the cloth holder and the receiver includes a guide and the other one of the cloth holder and the receiver includes a groove that accommodates the guide to allow the guide to slide along the groove,

wherein the cloth holder includes a securing device to secure the cloth holder to the receiver at a position at which the cloth holder slides and stops on the receiver.

4. The printer according to claim 1, further comprising a side wall surrounding the cloth accommodating space,
wherein the side wall is partially integrated into the base.

5. The printer according to claim 1, further comprising a side wall surrounding the cloth accommodating space,
wherein the side wall is movable between a position to surround the cloth accommodating space and a position to open the cloth accommodating space.

6. A cloth printing system comprising:
at one printer according to claim 1;
a printing instruction issuing device connected to the least one printer; and
at least one of a preprocessing device to apply a preprocessing process to the cloth and a heater to heat the cloth bearing the image printed by the at least one printer on the cloth,

the printing instruction issuing device connectable to the at least one of the preprocessing device and the heater, the printing instruction issuing device including a process controller to sequentially control the at least one printer and the at least one of the preprocessing device and the heater.

7. The cloth printing system according to claim 6, wherein the printing instruction issuing device is connectable to the preprocessing device and the heater,

wherein the process controller of the printing instruction issuing device sequentially controls the preprocessing device, the at least one printer, and the heater to execute the preprocessing operation, a printing operation, and a heating operation, respectively.

8. The cloth printing system according to claim 6, wherein the cloth holder includes an identification information storing device that stores identification information of the cloth holder,

wherein the printer, the preprocessing device, and the heater include detectors, respectively, to detect and send identification information held in the identification device to the printing instruction issuing device.

9. The printer according to claim 1, wherein:
the peripheral cover includes a plurality of side walls, and the plurality of side walls surround all sides of the cloth accommodating space between the platen and the base.

10. A cloth holder held by a receiver installed in a printer including a printing unit to reciprocate in a prescribed direction to and from the printing unit, the cloth holder comprising:

a base; and
a platen mounted on the base to hold a cloth to be printed by the printing unit with an image,

17

wherein the cloth holder is detachably attachable to the receiver in the prescribed direction while holding the cloth on the platen, and
wherein the cloth holder includes:

- a peripheral cover to sandwich the cloth together with the platen at a periphery of the platen;
- a cloth accommodating space formed between the platen and the base to accommodate a surplus portion of the cloth,
- wherein the peripheral cover encloses the cloth accommodating space.

11. The cloth holder according to claim **10**, wherein the cloth holder is detachably attachable to a heater to heat the cloth.

12. The cloth holder according to claim **11**, wherein the heater heats the cloth bearing the image on the cloth.

13. The cloth holder according to claim **10**, wherein the cloth holder is detachably attachable to a printing operation

18
preprocessing device that executes a preprocessing process before a printing operation is executed by the printer.

14. The cloth holder according to claim **13**, wherein the printing operation preprocessing device applies the preprocessing process to at least a region of the cloth to be printed with the image.

15. A holder with a cloth, the holder comprising:
the cloth holder according to claim **10**; and
the cloth held on the cloth holder,
wherein at least a portion of the cloth is held flat on the cloth holder.

16. The printer according to claim **10**, wherein:
the peripheral cover includes a plurality of side walls, and
the plurality of side walls surround all sides of the cloth accommodating space between the platen and the base.
